(57) **CLAIM**

The ornamental design for a bath positioner, as shown and described.

DESCRIPTION

FIG. 1 illustrates a top, left, front isometric view of a bath positioner showing a first embodiment of my new design; FIG. 2 illustrates a top, right, front isometric view thereof; FIG. 3 illustrates a right side view thereof; FIG. 4 illustrates a left side view thereof;

FIG. 5 illustrates a top, left, rear isometric view thereof; FIG. 6 illustrates a top, right, rear isometric view thereof; FIG. 7 illustrates a front left side elevational view thereof; FIG. 8 illustrates a front right side elevational view thereof; FIG. 9 illustrates a bottom, left, rear isometric view thereof; FIG. 10 illustrates a bottom, right, rear isometric view thereof;

FIG. 11 illustrates a right side bottom view thereof;

FIG. 12 illustrates a left side bottom view thereof;

FIG. 13 illustrates a top view thereof;

FIG. 14 illustrates a bottom view thereof;

FIG. 15 illustrates a rear view thereof;

FIG. 16 illustrates a top rear view thereof;

FIG. 17 illustrates a bottom rear view thereof;

FIG. 18 illustrates a front view thereof;

FIG. 19 illustrates a top front view thereof;

FIG. 20 illustrates a bottom front view thereof;

FIG. 21 illustrates a top view of a bath positioner with attachment suction cups according to a second embodiment thereof;

FIG. 22 illustrates a bottom view of FIG. 21;

FIG. 23 illustrates a right side view of FIG. 21;

FIG. 24 illustrates a front view of FIG. 21; and,

FIG. 25 illustrates a rear view of FIG. 2.
